UNITED STATES PATENT OFFICE.

DAVID H. COLES, OF NEW YORK, N. Y., AND FREDERICK CHARAVAY, OF JERSEY CITY HEIGHTS, NEW JERSEY, ASSIGNEES TO REQUA MOTOR COMPANY, A CORPORATION OF NEW YORK.

ROTARY DISTRIBUTING VALVE-BODY.

1,110,310.

Specification of Letters Patent. Patented Sept. 15, 1914.

Original application filed May 13, 1910, Serial No. 561,035. Divided and this application filed January 19, 1912. Serial No. 672,049.

To all whom it may concern:

Be it known that we, DAVID H. COLES and FREDERICK CHARAVAY, citizens of the United States, residing at New York, county of New York, State of New York, and at Jersey City Heights, county of Hudson, State of New Jersey, respectively, have invented certain new and useful Improvements in Rotary Distributing Valve-Bodies, of which the following is a specification, reference being had therein to the accompanying drawing.

This invention is a rotary distributing valve-body for use in internal combustion and other engines.

The object of the invention is to produce a valve-body which may be mounted in a proper cylindrical encasement suitably connected with engine cylinders; the valve-body being of a construction to receive and to distribute the gaseous or other mixture received by it, appropriately for high efficiency in a two-cycle or other engine.

In the accompanying drawings, Figure 1 is a side view, and Fig. 2 a lengthwise, central section at line 9—9 of Fig. 1, of our new valve-body. Fig. 3 is a rear elevation of a casing which contains a lengthwise-extending compression-chamber surrounding a rotary valve casing. This view shows ports for connection with three cylinders, and also shows water-jacket ports. Fig. 4 is a top plan view of said casing. Fig. 5 is a front elevation of said casing. Figs. 6 and 7 are lengthwise central complementary sections at line x—x of Fig. 4 of said casing, the rotary valve being removed. It is also removed from Figs. 3, 4 and 5. Fig. 8 is a lengthwise central view of the assembled casing and rotary valve, the latter being in one of its positions of use. This view also shows operating mechanism for the valve, and further shows ports for connection with an intake manifold not shown.

Referring to the drawings, the valve-body 21 is round in some, and partially round in other cross-sections, to form bearing walls x and bearing collars 26, here shown, with one exception, as circumferentially grooved to receive gaskets that are not shown. The end walls of the rotary valve-body are indicated by y, and these end walls are provided with intake ports 35. From the end walls y, in the particular form of valve-body

shown, the bearing ends 20 of the valve-body 55 oppositely project. The valve-body is lengthwise chambered between its end walls y, and its circumferential wall x is formed with a plurality of exit ports 23, which are preferably, and as shown, in staggered relation one to another, and spaced apart one from another. Through these exit ports the gas or fluid, received into the lengthwise chamber through the opposite inlet ports 35 in opposite ends of the valve-body, is discharged (into a pump, not shown). The circumferential wall of the lengthwise chamber is depressed at 24, opposite each exit port 23, and the valve-body is provided with circumferentially extending grooves 24^a, the 70 space of each of which communicates with the space of a depression 24. The function of each communicating space of a depression 24, and of a circumferentially extending groove 24^a, is to receive (gas from a pump 75 cylinder, not shown) and discharge the gas or other fluid when the valve-body is assembled with other parts (into a transfer chamber, not shown, whence the gas goes to the working cylinder of an engine, not shown). 80 Each exit port 23 is surrounded by a wall bearing surface, in part consisting of a portion x and in part of a collar 26; and, circumferentially considered, wall bearing portions x space the mouth of each exit port 85 apart from the opening or mouth of the space in a depression 24, intervening between the openings of said spaces, so as to separate said openings one from another when the valve-body is mounted in a cylindrical casing. The functions of the collar portions 26 are not only to form good circumferential bearing surfaces intermediate the ends of the valve-body, but in the present construction, also to form a side wall of a 90 groove 24^a. While, in the form of valve-body illustrated, only three exit ports and three circumferentially extending grooves 24^a are shown, the valve-body may be formed with varying numbers thereof, according to 100 the number of engine cylinders.

If it be desired to supply all the engine cylinders with fluid, at once, by means of a valve such as indicated, the exit ports 23 may be placed in line one with another; and 105 in some uses to which this valve may be put, the configuration or form of the communicating spaces of the depressions 24, and of

the circumferentially extending grooves 24^a, may be varied. In fact, the form of our new valve may be varied, without departure from our invention, in many respects, to suit different styles or forms of engine construction.

Referring to Figs. 3 to 8, inclusive, casing A is adapted for attachment in the form shown to three engine cylinders, as shown in our Patent No. 1,020,128 of March 12, 1912, of the application for which, this present application is a division. It contains a water-jacket chamber and ports 39 not material to the invention but shown; and its rear side is formed with three upper ports 16, one for each piston cylinder; and with three lower ports 17, one for each pump cylinder, as described in said patent. Casing A contains the gas-transfer chamber 10 in which more or less gas compression may occur, but a function of which is to collect the gas from the pump cylinders and to distribute the gas to the piston cylinders, as required. Chamber 10 may be also considered as a gas-storage chamber. It is formed by the end and outward walls of casing A and by the lengthwise-extending interior wall 22 which is interiorly round in cross section and serves as a bearing or housing for the rotary valve 21. Casing A is open on its front side as shown in Fig. 5, and this opening is closed gas-tightly by a cover. The rotary valve casing is provided with four ports *a* spaced apart around its circumference and each directly communicating with one of the spaces 24^a of the rotary valve. The adjacent group of ports *b*, arranged similarly to ports *a*, directly communicate with one of the spaces 24^a of the rotary valve; and another group of similarly arranged ports *c*, directly communicate with the remaining space 24^a of the rotary valve, all the ports as shown, pertaining to a three-cylinder engine. Gas is taken into the opposite ends of the rotary valve through its ports 35 which communicate with the ports 35^a of casing A. The parts indicated by 10^a are merely stud-like pieces of metal between the outward wall of casing A and wall 22.

What we claim, is,—

1. A rotatable valve-body having an exteriorly round, bearing surface; a lengthwise extending chamber the opposite end walls of which are each formed with an inlet port

and the circumferential side wall of which is formed with a plurality of exit ports, the circumferential wall of the valve-body having a depressed portion opposite each exit port and a circumferentially extending groove communicating therewith in combination with a valve casing having an interior cross-sectionally-round lengthwise-extending chamber for the valve body, and exteriorly to said chamber another lengthwise-extending chamber inclosing the wall of the interior chamber; the walls of said chambers being ported for the purposes described.

2. A rotatable valve-body formed with exteriorly round bearing surface portions and between its ends with a lengthwise extending chamber provided with a plurality of inlet ports spaced apart and a plurality of exit ports spaced apart and in staggered relation one to another; the circumferential wall being depressed opposite each exit port and spaced apart therefrom by intervening wall bearing portions of the valve-body in combination with a valve casing having an interior cross-sectionally-round lengthwise-extending chamber for the valve body, and exteriorly to said chamber another lengthwise-extending chamber inclosing the wall of the interior chamber; the walls of said chambers being ported for the purposes described.

3. The combination with a rotatable valve-body formed with exteriorly-round bearing surface portions, and between its ends with a lengthwise-extending chamber provided with a plurality of inlet-ports spaced apart, and a plurality of exit-ports spaced apart and in staggered relation one to another; the circumferential wall being depressed opposite each exit-port and spaced apart therefrom by intervening wall-bearing portions of the valve-body; of a casing comprising an exterior gas-chamber ported for connection with a plurality of engine cylinders, and an interior rotary valve chamber ported for communication with said exit ports.

In testimony whereof we affix our signatures in presence of two witnesses.

DAVID H. COLES.

FREDERICK CHARAVAY.
